VENDING MACHINE FOR NEWSPAPERS OR THE LIKE

Rune Pearson, Los Angeles County, Calif. (11645
McBean Drive, El Monte, Calif. 91732)

Filed Mar. 12, 1970, Ser. No. 21,870

Term of patent 14 years

Int. Cl. D20—01

U.S. Cl. D52—3

FIG. 1 is a front perspective view of a vending machine for newspapers or the like showing my new design;

FIG. 2 is an elevational view of the side opposite that shown in FIG. 1; and

FIG. 3 is a rear elevational view thereof.

I claim:

The ornamental design for a vending machine for newspapers or the like, as shown.
